UNITED STATES PATENT OFFICE.

GEORGE A. LORING AND GEORGE N. SEAMAN, OF BOSTON, MASSACHUSETTS.

DESIGN FOR A NAPKIN.

SPECIFICATION forming part of Design No. 24,936, dated November 26, 1895.

Application filed August 9, 1895. Serial No. 558,786. Term of patent 14 years.

To all whom it may concern:

Be it known that we, GEORGE A. LORING and GEORGE N. SEAMAN, citizens of the United States, residing at Boston, in the county of Suffolk and State of Massachusetts, have invented and produced a new and original Design for Napkins, of which the following is a specification, reference being had to the accompanying fac-simile drawing, forming part thereof.

The drawing herewith presented illustrates in plan a napkin embodying our design.

The essential features of our design comprise a number of badges symbolic of military organizations, grouped to form a border for a napkin wholly or in part about the edge.

The particular features of our design are embodied in a rectangular space A, created by a border-line, which is continuous along two opposite sides, but interrupted on the two adjacent corresponding sides, thus forming

openings. Within said openings and positioned partly in the border-space and partly in the body portion of the napkin appear two badges, respectively, 13. Midway of the continuous border-lines and wholly within the body portions of the napkin are two other badges 24. Within the space included within the border-lines and the edge of the napkin and constituting the ornamentation therefor are grouped numerous badges, which are symbolic of various military organizations.

What we claim is—

The design for a napkin as herein shown and described.

In testimony whereof we affix our signatures in presence of two witnesses.

GEORGE A. LORING.
GEO. N. SEAMAN.
